CLAIM

The ornamental design for a lotion roller applicator, as shown.

DESCRIPTION

FIG. 1 is a perspective view of a lotion roller applicator showing our new design;

FIG. 2 is a top plan view thereof, on a reduced scale;

FIG. 3 is a left side elevational view thereof, the right side being a mirror image;

FIG. 4 is a front end elevational view thereof;

FIG. 5 is a rear end elevational view thereof; and

FIG. 6 is a bottom plan view thereof.
